UNITED STATES PATENT OFFICE.

FREDERICK JACOB, OF NEWARK, ASSIGNOR OF ONE-FOURTH TO HENRY PATTBERG, OF JERSEY CITY, NEW JERSEY.

CAR-CO尤LING.

SPECIFICATION forming part of Letters Patent No. 504,085, dated August 29, 1893.

Application filed May 4, 1893. Serial No. 472,930. (No model.)

To all whom it may concern:

Be it known that I, FREDERICK JACOB, a citizen of the United States, residing in the city of Newark, in the county of Essex, State 5 of New Jersey, have invented certain new and useful Improvements in Car-Couplings, of which the following is a specification.

This invention has reference to an improved car-coupling by which the coupling of the 10 cars is accomplished by the force of gravity, so as to dispense with the use of springs, screws and other parts that are liable to wear out by use and which is so constructed that a double interlocking of the draw-heads takes 15 place, and that the uncoupling of the cars can be accomplished either from the side, platform or top of the car without danger to life or limb. The draw-bars can also be used with the ordinary pin and link-coupling, so as to 20 permit of coupling with cars having the old style pin and link while the draw-heads adapt themselves readily to different angles of inclination toward the drawbars when rounding curves, so that a steady and reliable connection of the cars is obtained.

The invention consists of a car-coupling which consists of a drawbar which is open at the sides and has a rounded-off face-plate with an opening for the ordinary link, the upper 30 part of the face-plate being made tapering at both sides, so as to support a saddle-piece which is inclined in opposite directions and connected by a swivel-pin with the yoke-shaped top-piece of a detachable draw-head 35 which rests on the saddle-piece. The draw-head is open at the center for the face-plate of the draw-bar and provided with straight face-plates at both sides of the draw-bar. A weighted push-piece is hinged to the rear-side 40 of the drawhead, its lower end projecting through an opening in the draw-head and having a bent-up stop-lug back of the opening, against which lug abuts the arm of a pivoted latch which is made integral with a coupling 45 hook at its outer end, while a weighted latch-lever is fulcrumed to said latch and connected by a pivot-link with a transverse uncoupling lever fulcrumed to the top-piece of the draw-head. The coupling-hook extends around the 50 edge of the draw-head to the front of the same, so as to couple with the draw-head of the car

to be coupled, when the latch is dropped in its lowermost position. The latch is operated in connection with the push-piece, so as to retain the coupling-hook in coupled or uncoupled position, as required. 55

The invention consists further of certain details of construction, which will be fully described hereinafter and finally pointed out in the claims. 60

In the accompanying drawings, Figure 1, represents a side-elevation of my improved car-coupling, showing the parts in uncoupled position. Fig. 2, is a plan-view of Fig. 1. Fig. 3, is a front-elevation of the draw-bar 65 and draw-head, ready for coupling. Fig. 4, is a side-elevation of the car-coupling showing the parts in coupled position. Fig. 5, is a plan-view of Fig. 4. Fig. 6, is a front-view of the draw-bar and draw-head in coupled position. 70 Figs. 7 and 8 are rear-elevations of the draw-head, showing the push-piece in vertical transverse section, and the parts respectively in uncoupled and coupled position. Figs. 9, and 10, are vertical transverse sections re- 75 spectively on line 9 9, Fig. 7, and 10—10, Fig. 8, and Fig. 11, is a detail horizontal section on line 11—11, Fig. 8.

Similar letters of reference indicate corresponding parts. 80

Referring to the drawings A represents a draw-bar, which is preferably made of plate-steel, open at the sides and provided with a rounded-off face-plate a, having an opening of sufficient size to permit the introduction of 85 a link when the draw-bar is to be used with the ordinary pin and link coupling. The draw-bar A is attached to the under side of the car-body in the usual manner and cushioned by suitable springs. The front or face-plate a of the draw-bar A is extended in upward direction and inclined from the center toward the sides, the curvature of the face-plate being concentric to a swivel-pin B which is passed through holes in the top and bottom- 90 plates of the draw-bar. On the top of the draw-bar A is supported, back of the top-part of the face-plate a, a saddle-piece C, the inclined sides of which correspond to the inclined top-part of the face-plate a, said saddle-piece being provided with flanges b b at 95 both sides, so as to rest steadily by gravity on 100

the sides of the top-plate of the draw-bar. When the draw-bar A is made specially for this construction, the saddle-piece is made in one integral piece with the draw-bar. The 5 saddle-piece C is likewise provided with a hole for the swivel-pin B. A draw-head D rests on the saddle-piece C and is connected with the saddle-piece and draw-bar by the pin B, it being provided with a backwardly-extending 10 yoke-shaped top-part d that corresponds in cross-section with the shape of the saddle-piece C. The lower part of the draw-head D is also provided with a yoke-shaped bottom-part d' which is like the top-part d, engaged by the pin 15 B, as shown clearly in Fig. 1. From the yoke-shaped back and bottom-parts d d' of each draw-head D extend horizontal side-portions or wings d², which serve to reinforce the face-plates. The wings d² at one side of the draw- 20 head are connected at the outer edges by a vertical plate d³, which is provided with an oblong opening d⁴, as shown clearly in Figs. 1, 3, 7 and 8. The draw-head D is preferably made of strong plate-steel and is bent into 25 shape by means of suitable dies so as to fit over the saddle-piece C of the draw-bar, it being open at its middle-portion, so as to permit the rounded-off face-plates to project slightly through the open portion of the draw- 30 head D. To the yoke-shaped top-part of the draw-head D is fulcrumed an uncoupling lever E, which is connected by a link e with a lever E', that is weighted at its outer end and fulcrumed to a latch F, which is pivoted at 35 its inner end to the rear-side of the draw-head D. The outer end of the latch F is bent in the shape of a hook F' that extends over the edge and over the front of the draw-head D, as shown clearly in Figs. 1, 3 and 6. The latch 40 F is provided below its pivot with a downward-extending arm f, that serves to engage an upwardly-bent lug g of the weighted push-piece G, which is pivoted at its upper end to 45 ears at the under side of one of the lateral wings d² of the draw-head, while the lower end projects through an opening in the face-plate of the draw-head D to the outside of the same, the lower end being provided with a suitable head or enlargement g', as shown in 50 Figs. 1, 2 and 3 and on a larger scale in Figs. 9, 10 and 11. The upwardly-bent lug g serves as a stop by which the push-piece G is prevented from being forced by its weight to too great a distance beyond the face of the draw-head, while the head g' limits the inward motion of the push-piece G, when the draw-heads 55 come in contact with each other. The uncoupling-lever E extends transversely across the draw-bar and is made of sufficient length 60 to permit the operation of the same from the sides, platform or top of the car, so that the brakeman is not required to pass in between the cars when coupling the same.

Operation of coupling: When the cars are 65 to be coupled, the parts are placed in uncoupled position and the coupling-hook of

each draw-head is placed in raised position by the uncoupling lever E and retained in this position by the inner end of the weighted latch-lever abutting against the lug g of the 70 push-piece G, as shown in full lines in Fig. 3 and in dotted lines in Fig. 7. The head g' of the push-piece G projects to its full extent beyond the face-plate of the draw-head. When, by the approach of the cars, the face- 75 plates of the draw-bars abut against each other, the draw-heads of both couplings form contact with each other, and the projecting heads of the push-pieces G are pushed inwardly, so that the inner ends of the weighted 80 latch-levers are released from the lugs g and dropped by their weights into the lowermost position, as shown in Figs. 6 and 8. In this position the coupling-hooks of the latches F engage the opposite sides of the draw-heads, 85 so that they are locked together at two diagonally-opposite points, as shown in Fig. 4. When the cars are to be uncoupled, each uncoupling lever E is turned on its fulcrum in such a position, that the latch-lever E' is 90 raised into the position shown in Fig. 3 and in dotted lines in Fig. 7. As the face-plates of the draw-heads are still in contact with each other, the inner end of the latch-lever E' engages the bent-up lug g of the push- 95 piece G. As soon as the draw-heads are moved away from each other, the push-pieces G are dropped by gravity until stopped by the contact of the lugs g with the face-plates of the draw-heads D, so that the arms f of the 100 latches F abut against the lugs g, as shown in Figs. 7 and 9. As the coupling-hooks F' are withdrawn from the face-plates of the draw-heads, the cars are ready to be uncoupled. The lower ends or heads G' of the push-pieces 105 G are projected beyond the face-plates of the draw-heads to their full extent. When the cars are coupled again, the heads of the push-pieces are pushed back, the latches are released and all the parts of the coupling, 110 namely, the uncoupling lever E, the coupling-hook F', the latch F and the latch-lever E' are dropped into the lowermost or coupled position, as shown in Figs. 8, 10 and 11. The intermediate position of the parts F, E', and 115 E and G is only produced when the uncoupling of the cars and the separation of the draw-heads takes place. When the cars are disconnected, the parts are set again by the uncoupling lever from the coupled or lowermost position into the uppermost or uncoupled position, as shown in Fig. 3.

Advantages: My improved car-coupling has a number of advantages as compared with the car-couplings heretofore in use, to wit:

First. The steady connection of the couplings by the face-plates of the draw-heads.

Second. The yielding of the draw-heads when the cars approach each other for coupling on a curve, so as to facilitate the connection of the parts. This yielding of the draw-heads also takes place when the cars pass

around curves, which is accomplished by the swivel-pins of the draw-heads, on which the draw-heads swing. During the swinging motion of the draw-heads, when rounding curves, 5 the yoke-shaped top-parts of the same ride on the saddle-pieces of the draw-bars and are returned to their original positions by the force of gravity, the yoke-shaped top-parts of the draw-heads and the saddle-pieces of the 10 draw-bars securing always the proper alignment of the parts, as soon as the cars have passed around the curve.

Third. As each draw-head is provided with a coupling-hook, the double locking of the 15 drawheads at diagonally-opposite points of the same is produced, so that the accidental uncoupling of the cars is prevented.

Fourth. The uncoupling can be accomplished from the side, platform or top of the 20 car without the slightest danger to the brakeman operating the same.

Fifth. My improved coupling can be used 25 for coupling with the ordinary link, as the link can be readily inserted through the opening in the rounded-off face-plate of the draw-bar and coupled by the swivel-pin of the draw-head, which pin is dropped through the link and draw-bar and becomes thereby the coupling-pin for the link, a reserve-link being 30 preferably carried on each draw-bar for this purpose, as shown in Figs. 1 and 4.

Having thus described my invention, I claim as new and desire to secure by Letters Patent—

35 1. The combination, with a draw-bar having a rounded-off face-plate, of a saddle-piece on said draw-bar, a draw-head having a yoke-shaped top-part resting on said saddle-piece, and a swivel-pin for connecting the draw-head 40 with the saddle-piece and draw-bar, substantially as set forth.

2. The combination, with a draw-bar being open at the sides and having a rounded-off face-plate, of a saddle-piece on the draw-bar, 45 said saddle being provided with side-flanges for being retained on the top of the draw-bar, a draw-head resting on the saddle-piece and a swivel-pin connecting the draw-head, saddle-piece and draw-bar, substantially as set 50 forth.

3. The combination, of a draw-bar having a rounded-off face-plate, a saddle-piece resting on the top of the draw-bar, a draw-head having a yoke-shaped top-part resting on said 55 saddle-piece, yoke-shaped top and bottom-parts, face-plates, and horizontal wings at both sides at the top and bottom-yokes, and a swivel-pin for connecting the yoke-shaped portions of the draw-head with the saddle- 60 piece and draw-bar, substantially as set forth.

4. In a car-coupling, the combination, of a draw-head, a weighted push-piece pivoted to the rear-side of the draw-head and arranged at right angles thereto, its lower end passing 65 through an opening in the face-plate of the draw head to the front of same, a latch piv-

oted to the rear-side of the draw-head and provided with a coupling-hook at its outer end, a weighted latch-lever pivoted to the latch, an uncoupling-lever fulcrumed to the 70 top-part of the draw-head and connected by a link with the latch-lever, and means for retaining the latch and weighted latch-lever, so as to retain the parts in uncoupled or partly coupled position, substantially as set forth. 75

5. The combination, of a draw-head, a weighted push-piece pivoted to the rear-side of the draw-head at right angles thereto, the lower end of the push-piece extending through an opening in the draw-head to the front of 80 same, said push-piece being provided with an upwardly-bent side-lug, a latch pivoted to the rear-side of the draw-head and provided with a stop-arm, a weighted latch-lever pivoted to the latch and an uncoupling-lever fulcrumed 85 to the top-part of the draw-head and connected by a link with the latch-lever, the stop-arm on the inner end of the latch engaging the lug of the push-piece, when the parts are in partly uncoupled position, substantially as 90 set forth.

6. The combination, of a draw-bar, a saddle-piece on the top of the draw-bar, a draw-head having a yoke-shaped top-part resting on the saddle-piece of the draw-bar and a 95 swivel-pin connecting the top-part of the draw-head, saddle-piece and draw-bar, the front of the draw-bar being rounded off so as to permit the swinging of the draw-head on the coupling-pin, and the riding of the top-piece of the draw-head on the saddle of the draw-bar and the return of the same by gravity into normal position, substantially as set 100 forth.

7. A draw-head, provided with a central 105 opening, a face-plate at each side of the opening, a yoke-shaped top and bottom-part and horizontal wings at each side of the said top and bottom-parts for reinforcing the face-plates, substantially as set forth. 110

8. A draw-head, provided with a central opening, a face-plate at each side of said opening, a yoke-shaped top and bottom-part, horizontal wings at each side of the top and bottom-parts and a vertical connecting side-plate 115 for the wings at one side of the draw-head, said side-plate having an elongated opening or slot, substantially as set forth.

9. The combination, of a draw-bar having a rounded-off face-plate and an opening in 120 said face-plate for coupling with an ordinary link, with a draw-head swiveled to the draw-bar and provided with a central opening, substantially as set forth.

10. The combination, of a draw-bar, a saddle-piece on the top of said draw-bar, a draw-head resting on said saddle-piece, a swivel-pin for connecting the draw-head, saddle-piece and draw-bar, a weighted push-piece hinged to the rear-side of the face-plate of the 130 draw-head and projecting beyond the same, a latch pivoted to the face-plate of the draw-

head and provided with a coupling-hook at its outer end, a weighted latch-lever pivoted to the latch, an uncoupling lever fulcrumed to the top-part of the draw-head and a pivot-link connecting the latch-lever and uncoupling-lever, substantially as set forth.

5 In testimony that I claim the foregoing as

my invention I have signed my name in presence of two subscribing witnesses.

FREDERICK JACOB.
